(57) **CLAIM**

The ornamental design for a sensorized insert for footwear as shown and described.

DESCRIPTION

FIG. 1 is a top perspective view of a sensorized insert for footwear in accordance with said design;

FIG. 2 is a bottom perspective view of the sensorized insert for footwear of FIG. 1;

FIG. 3 is a top view of the sensorized insert for footwear of FIG. 1;

FIG. 4 is a bottom view of the sensorized insert for footwear of FIG. 1;

FIG. 5 is a left side view of the sensorized insert for footwear of FIG. 1;

FIG. 6 is a right side view of the sensorized insert for footwear of FIG. 1,

FIG. 7 is a front end view of the sensorized insert for footwear of FIG. 1; and,

FIG. 8 is a rear end view of the sensorized insert for footwear of FIG. 1.

The portions shown in broken lines form no part of the claimed design.

The characteristic feature resides in the arrangement of the sensor elements.
